Primary Examiner — T Chase Nelson*Assistant Examiner* — Sydney Margaret Parsley(74) *Attorney, Agent, or Firm* — MUNCY, GEISSLER, OLDS & LOWE, P.C.(57) **CLAIM**

The ornamental design for a scaffolding component as shown and described.

DESCRIPTION

FIG. 1 is a bottom view of a scaffolding component showing our new design;

FIG. 2 is a rear view thereof;

FIG. 3 is a right-side view thereof;

FIG. 4 is a top view thereof;

FIG. 5 is a left-side view thereof;

FIG. 6 is a front view thereof; and,

FIG. 7 is a perspective thereof.
